UNITED STATES PATENT OFFICE.

WILLIAM TURES, OF CHICAGO, ILLINOIS, ASSIGNOR TO THE ORO-TONE CO., OF CHICAGO, ILLINOIS, A CORPORATION OF ILLINOIS.

SOUND-BOX COUPLER.

Application filed June 20, 1919. Serial No. 305,613.

My invention relates in general to talking machines and more particularly to improved means for adjustably mounting a sound box on a tone arm.

5 The records made by different manufacturers differ in the number of grooved convolutions to the inch. The speed of the movement of the tone arm radially of the record consequently differs when different 10 makes of records are played. Those machines in which the tone arm is moved radially of the record through the engagement of the needle with the groove may play different makes of records by merely providing 15 an adjustable connection between the sound box and tone arm so as to properly position the sound box for hill and dale and zigzag records. A talking machine such as the Edison, however, in which the tone arm is 20 positively moved radially of the record in synchronism with the spaced relation of the grooved convolutions can play only the particular records for that machine, i. e., records having the number of grooved convolutions 25 to the inch corresponding to the rate of movement of the tone arm.

The primary object of my invention is to provide a sound box coupling for attachment to the end of the tone arm which will permit 30 the sound box to have a rate of radial movement different from that at which the tone arm is oscillated, thereby enabling talking machines having positively driven tone arms to play records whose grooved convolutions 35 per inch do not correspond with the positive movement of the tone arm.

A further object of my invention is to provide a coupling for connecting a sound box to a tone arm of the nonvertically moving 40 type, such as the tone arm of an Edison machine which will permit the sound box to oscillate vertically relatively to the tone arm, thereby compensating for unevenness in the record or turn-table, permitting free rise 45 and fall of the sound box as the needle follows the groove, and enabling the sound box to be swung upwardly to a position convenient for the removal and insertion of needles.

50 A still further object of my invention is to provide a coupling for uniting a sound box with a tone arm which may be readily adjusted to properly position the sound box for both zigzag and hill and dale records.

And a further object of my invention is to 55 provide a sound box coupling which may be simple in construction, convenient in use and efficient in operation.

My invention will be more fully disclosed hereinafter with reference to the accompanying 60 drawing in which the same is illustrated as embodied in a convenient and practical form, and in which:

Figure 1 shows an elevational view of the preferred form of my invention with the 65 sound box arranged to play records with zigzag undulations.

Figure 2 is an elevational view of my invention showing the sound box turned to play a hill and dale record. 70

Figure 3 is a vertical sectional view taken on the longitudinal central plane through the sound box coupling on line 3—3 of Fig. 4 and

Figure 4 is a vertical section on line 4—4 75 of Figure 3.

Generally speaking I accomplish the objects of my invention by providing a tone arm coupling having a vertical hinge which compensates for uneven records and turn-tables of different height, and permits the rise and fall of the sound box as records are being reproduced and also permits the sound box to be turned back for the removal and insertion of needles. I provide also for 80 horizontal movement, that is, movement about a vertical axis, which movement compensates for the difference in the number of convolutions per inch of the various kinds of records now on the market and permits 85 them to be played on machines having a mechanical feed as the Edison, for moving the tone arm, such horizontal play allowing a swinging movement of the sound box with respect to the end of the positively moved 90 tone arm when records other than Edison records are played. I also provide a telescopic sleeve connection whereby vertical movement of the sound box may be permitted while at the same time escape of the 95 sound waves is prevented and admission of air and dirt to the interior of the tone arm 100 prevented.

In the drawings, 5 is the end of a tone arm. In the form shown it has an enlarged 105 portion 6 adapted to receive the sleeve 7 of my sound box connector, the sleeve 7 being provided with a pin 8 for cooperation with

the usual bayonet joint slot in the end of the tone arm 5. The sleeve 7 terminates in an enlarged collar 9 wherein is formed an annular recess containing a gasket 10 of rubber or similarly resilient material. The gasket may be secured in place by adhesion or in any manner desirable. The top portion of the enlargement 9 is provided with a pair of ears 11 between which is pivoted a portion of a vertical hinge, this portion comprising the lug 12. The lug 12 extends upwardly from a horizontally disposed intermediate member 13 which member has a shoulder 14 to abut the end of the sleeve 7 and an inwardly extending collar 15 adapted to extend within the gasket 10, the length of the collar 15 being sufficient so that at all times it may extend within the gasket irrespective of the amount of vertical play in the sound box while operative in the reproduction of records. The member 13 has an air chamber 13^a communicating with one end of a chamber 16^a in a member 16 having a vertical portion and an obliquely disposed portion 17, the same forming an angular bend for the travel of the sound waves from the sound box to the tone arm. The member 16 is mounted on the member 13 to rotate thereon to permit swinging of the sound box about a vertical axis. The member 16 is held in engagement with the member 13 by means of a threaded pin 18 arranged as shown and which pin is secured in position by means of a set screw 19 inserted in a proper portion of the member 13. The downwardly directed member 17 has an enlarged end 20 for the reception of the tone arm connector on the rear portion 21 of the sound box, the member 20 being provided with a slot 22 to receive a pin 21^a on the member 21 of the sound box as in the usual construction. However, I may secure the sound box to the member 22 by any suitable means. The length of the slot 22 is such as to permit the sound box to be moved from the position shown in Figure 1 to that shown in Figure 2 or vice versa and to permit no further angular movement of the sound box with respect to the end 20. In practice this movement is substantially 90 degrees so that the plane of the diaphragm may be positioned to reproduce either hill and dale, or zig zag records.

Referring to Figure 3, it will be observed that as the connector of my invention is moved about the horizontal hinge, that is the one between the lugs 12, the collar 15 will move relatively to the gasket 10. However, by reason of the provision of the gasket 10 escape of the sound waves from the tone arm channel is prevented and also the admission of dirt or air currents into the tone arm is prevented. When it is desired to replace a needle the whole device may be swung upwardly about the hinge 11 bring-

ing the needle above the tone arm whereupon the needle may be applied in the usual manner.

The operation of my invention is as follows:

The member 7 of the coupling is connected to the end of the tone arm 5 in the manner above described, and the sound box swung to the position shown in Figure 1 when a zigzag record is played, or to the position shown in Figure 2 for a hill and dale record. Assuming that the record being played has a number of grooved convolutions to the inch different from the record for which the tone arm 5 is positively moved, the sound box will move radially of the record at a rate differing from the movement of the end of the tone arm, such differential movement being permitted by the swinging of the sound box horizontally with respect to the end of the tone arm owing to the oscillation permitted between the members 13 and 16 of the coupling about their vertical axis. Assuming that the tone arm 5 is of the type movable horizontally, but not vertically, the sound box oscillates about the horizontal axis of the members 7 and 13, thereby compensating for unevenness in the record or in the turn-table which supports the record, and to permit the free rise and fall of the sound box as the needle thereof follows the groove of the record. The hinge 11 also permits the sound box to be swung upwardly into a convenient position for removing a worn needle and substituting therefor a new one.

From the foregoing description it will be observed that I have invented a coupling for uniting a sound box to a tone arm by means of which a talking machine having a positively moved tone arm may play records having grooved convolutions of different numbers to the inch from those of the record for which the talking machine is intended to be used. It will be further observed that my invention permits a sound box to be so mounted upon the end of a tone arm incapable of moving vertically as to permit the sound box to have a vertical movement relatively to the end of the tone arm. It will be further evident that my invention permits the playing of either hill and dale or zigzag records by merely swinging the sound box about the vertical axis of its coupling so as to properly position the diaphragm for the character of record to be played.

While I have described more or less precisely the details of construction, I do not wish to be understood as limiting myself thereto, as I contemplate changes in form and proportion of parts and the substitution of means as circumstances may suggest or render expedient without departing from the spirit of my invention.

I claim:

1. A coupler adapted to operatively connect a sound box and a tone arm constrained as to both horizontal and vertical movement, said coupler comprising a member adapted to be rigidly connected to the tone arm, a second member attached to said first member by means of a horizontal pivot, and a third member connected to said second member by means of a vertical pivot, said third member being formed with a connection serving to engage a sound box in such manner that the sound box may be rotated about the axis of the member.
- 15 2. A coupler adapted to operatively connect a sound box and a tone arm constrained as to both horizontal and vertical movement, said coupler comprising a member adapted to be rigidly connected to the tone arm, a second member attached to said first member by means of a horizontal pivot located above the tone arm whereby the member may be swung above the tone arm, and a third member connected to said second member by means of a vertical pivot, said third member being formed with a connection serving to engage a sound box in such manner that the sound box may be rotated about the axis of the member.
- 20 3. In a talking machine, in combination with a sound box and a tone arm, of a coupler, said coupler comprising a member secured to and in alignment with the tone arm, a second member pivotally connected with
- 25 the first member to swing about a horizontal axis, a tubular projection on one of said members in telescopic engagement with the other member, a gasket interposed between said members, and a third member in engagement with said sound box, said sound box and third member having interengageable means whereby the sound box may be turned through an angle for reproducing either zig-zag or hill-and-dale records.
- 30 4. A sound box coupling including a plurality of members one of which members is

adapted for connection with the tone arm, another adapted for connection with the sound box, and a third connecting said first and second members, pivoted connections 50 permitting relative swinging movement between said members whereby the sound box may be swung both vertically and horizontally, and a pivoted connection whereby said sound box may be turned within its member 55 through an angle.

5. A coupling for connecting sound boxes to tone arms, including a member adapted for engagement with the tone arm, a second member connected to said tone arm member 60 by means of a horizontal pivot adapted to permit swinging movement of said member, a third member adapted for cooperation with the sound box and connected thereto in such manner as to permit turning the sound 65 box through an angle of substantially 90 degrees, said third member being connected to said swinging member, and means permitting relative horizontal rotation between said swinging member and said sound box 70 member.

6. In a talking machine, in combination with a sound box and a tone arm, of a coupler, said coupler comprising a member secured to and in alignment with the tone arm, 75 a second member pivotally connected with the first member to swing about a horizontal axis, a tubular projection on one of said members in telescopic engagement with the other member, a gasket interposed between 80 said members, and a third member in engagement with said sound box, said third member being rotatable relative to said second member about a vertical axis, and said sound box and its connector having interengageable means whereby the sound box 85 may be turned through an angle for reproducing either zig-zag or hill-and-dale records.

Signed at Chicago, Illinois, this 7th day 90 of June 1919.

WILLIAM TURES.
